UNITED STATES PATENT OFFICE

LEON H. KRAMER, OF BROOKLYN, NEW YORK

CONTAINER FOR FLUIDS

Application filed January 31, 1929. Serial No. 336,589.

This invention relates to containers for fluids and more particularly to a container for a cleaning fluid, which container is adapted to eject a predetermined amount of fluid 5 on the surface to be cleaned.

This invention has particular application when used as a container for a cleaning liquid for eye-glasses. In the prior art such cleaning liquids have been deposited in bottles 10 and when required for use have been ejected through a small Venturi meter, or what is commonly known as an atomizer. Such a device, while satisfactory after a fashion for use in an office, cannot be transported, and 15 has the further disadvantage that the exact amount of liquid required cannot always be obtained by pressure on the rubber bulb. Also the atomized liquid is not wholly deposited on the surface to be cleaned but is diffused through the surrounding space. In another form of container, the liquid is forced 20 out through a small opening by means of violent shaking. Besides rattling the temper of the user and spattering the liquid everywhere but on the desired eye-glass, this method very 25 often results in collision between the container and the eye-glass, with consequent breaking of either or both.

In my invention, on the other hand, the 30 exact amount to be deposited on the glass or other surface is obtained by a simple movement of the thumb. This movement deposits a drop of predetermined size on the surface to be cleaned, and the container has the particular advantages that it can be easily transported without danger of spilling of the liquid or of breaking of the container, and that there is never any danger of breaking the eye-glass. 35

The invention will be better understood by reference to the accompanying drawings, in which

Fig. 1 represents a plan view of a container 40 according to my invention, with the cover partially in section;

Fig. 2 is a longitudinal section through the container;

Fig. 3 is an enlarged view showing the construction of the ejecting means;

Fig. 4 is an enlarged view showing a modification of the ejecting button;

Fig. 5 is an enlarged view showing a preferred form of glass tip; and

Fig. 6 is a view showing the cover for the 55 container, with a portion thereof in section.

The device comprises a soft rubber tube 2 which has a tapered portion 3 at one end thereof. Around the soft rubber tube and spaced therefrom is a casing or envelope 4 of hard rubber, metal or similar material, which envelope has a tapered portion 5 to accommodate the tapered portion 3 of the soft rubber tube. A small length of glass tubing 7 is attached to the tapered portion 60 3. The glass tubing 7 may be straight or tapered, and may have either a straight bore or a spiral bore, or a plurality of such bores. Preferably I employ a piece of tubing having a plurality of spiral bores 6, as shown in 65 Fig. 5. These permit greater control over the amount of fluid to be ejected. Obviously, the amount of fluid to be ejected may be varied by varying the size and number of 70 bores in the glass tubing. The portion 5 of the envelope has a small opening through 75 which projects a button 8.

The sides of the member 8 taper downwardly as shown in the figures to permit 80 movement downwardly through the opening in the portion 5 but not upwardly. This member 8 may be of hard rubber or metal of the same color to match the envelope 4 or may consist of soft rubber to permit a better grip by the thumb. Underneath the member 8 is attached, by cement or otherwise, a small cushion 9. This cushion 9 consists of soft rubber or similar material and is adapted to contact with the tapering portion 3 of the soft rubber tube. If desired, members 8 and 9 may constitute one piece, 85 as shown in Fig. 4.

It will be obvious that when liquid is contained in the rubber tube 2, pressure of the thumb on the member 8 will compress the portion 3 of the soft rubber tube and eject a small amount of liquid through the glass tip 7. The amount of liquid so ejected may be controlled by varying the thickness of the cushion 9, as well as by varying the glass 90 100

tip 7. To prevent accidental pressure on the member 8 a locking means 12 may be provided to prevent downward movement of the member 8. This locking member 8 slides into position through a groove 25 in the casing 5.

To fill the receptacle 2 there is provided a long rod 13 which contacts with a lever 14 pivoted on a pin 15 in the casing 4. When the lever 14 is turned the rod 13 will compress the soft rubber casing 2, thus creating a suction and permitting ingress of the liquid through the tip 7. The lever 14 is so designed that it locks when in its normal position. If desired, the other end of the soft rubber tube 2 may be provided with an opening to permit insertion of the cleaning liquid. This opening may be closed by a cork stopper 17. The similar end of the casing 4 has an opening which is adapted to be closed by a screw member 18.

A cover 19 is provided to protect the glass tip 7 and tapered portion 5 of the container and has threads 22 to mate with the threads 24 on the container. If desired, a clip 23 may be provided on the cover 19 to permit clamping in a pocket.

The operation of the device is as follows: To fill the container, the tip end 7 is inserted into the liquid and the lever 14 is turned so as to compress the soft rubber tube. The atmosphere will then force the cleaning liquid into the containing tube 2. If desired, the liquid may be inserted through the other end of the tube after the cork member 17 and the screw member 18 have been removed. When it is desired to deposit a drop of the cleaning fluid on the eye-glass the thumb depresses the member 8 once and the exact amount comes out through the tip 7. If more liquid is necessary the member 8 is depressed again. It should be noted that the member 8 contacts with the tapered portion 3 so as to furnish a greater control over the amount of liquid to be ejected.

It will, therefore, be seen that with this device the required amount of fluid can be ejected when desired, and only when desired, with absolute safety to the article to be cleaned, to the container, and to surrounding objects and persons. The device is small, adjustable, transportable, and extremely efficacious for the purposes desired.

This device may be used to contain perfume, oil, medicated liquids or other substances that can be made to flow under pressure and which are required in predetermined amounts.

The applicant does not wish to be limited to the exact structure or proportions shown in the figures, but is to be limited only as set forth in the following claims.

Claims:

1. A container for fluids, comprising a soft rubber inner tube, a protecting outer casing,

means for ejecting a predetermined amount of the fluid from the inner tube, means for locking the ejecting means, and means for compressing the inner tube to permit ingress of the fluid.

70

2. A container for fluids, comprising a compressible inner tube tapered at one end, the tip of the tapered portion being open, a protecting outer casing similarly tapered, the tapered portion of the outer casing having a lateral opening therein, means projecting through this opening for ejecting the fluid from the tapered portion of the inner tube, and additional means for compressing the inner tube to permit ingress of the fluid through the same opening in the tapered portion of the inner tube.

75

3. A container for fluids, comprising a compressible tube, means for compressing the tube to eject fluid from one end thereof, means for compressing the tube to inject fluid into the same end, and removable means at the other end of the tube for permitting ingress of the fluid thereto or egress therefrom.

80

4. A container for fluids, comprising a compressible tube, a glass tip at one end of the tube, means for ejecting a predetermined amount of fluid through the glass tip, means for injecting fluid through the glass tip, and a protecting cover for the glass tip.

85

5. A container for fluids, comprising a compressible inner tube tapered at one end, the end of the tapered portion being open, a glass tube attached to the open end, a protecting outer casing covering all portions of the compressible inner tube and a portion of the glass tip, means for compressing the inner tube for injecting fluid into the inner tube through the glass tip, means for ejecting fluid from the inner tube through the glass tip, and removable means for covering the glass tip.
